DESIGN.

—o—

F. MANKEY.

PANEL.

No. 17,114.

Patented Feb. 15, 1887.

UNITED STATES PATENT OFFICE.

FREDERICK MANKEY, OF WILLIAMSPORT, PENNSYLVANIA.

DESIGN FOR A PANEL.

SPECIFICATION forming part of Design No. 17,114, dated February 15, 1887.

Application filed December 30, 1886. Serial No. 223,054. Term of patent 7 years.

To all whom it may concern:

Be it known that I, FREDERICK MANKEY, of Williamsport, Lycoming county, Pennsylvania, have invented and produced a new and original Design for Panels, of which the following is a specification.

My design, which is represented in the accompanying photograph forming part hereof, consists in the rectangular elevation A and the two smaller rectangular elevations, B and C, with intermediate channels, D and E. The edges or sides of all of said elevation appear in the form of steps, or, in other words, each of said elevations has the appearance of being made up of a series of elevations superposed

and gradually diminishing in area. The number of steps should preferably be more than two. Four are shown in the photograph. The upper surfaces of said elevations are flat.

I claim—

The design for a panel, substantially as herein shown and described, which consists in the rectangular elevations A, B, and C and intermediate channels, D and E, the sides of said elevations appearing in the form of steps.

FREDERICK MANKEY.

Witnesses:

C. F. MANKEY,
LOONHARD KNAUSS.
